UNITED STATES PATENT OFFICE.

HOWARD M. DUDLEY, OF PHILADELPHIA, PENNSYLVANIA.

FABRIC-STEAMING DEVICE.

1,314,791.

Specification of Letters Patent.

Patented Sept. 2, 1919.

Application filed April 23, 1917. Serial No. 163,798.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Fabric-Steaming Devices, of which the following is a specification.

My invention relates to fabric-steaming machines and refers particularly to a machine of this character suitable for steaming textile fabrics while under tension.

The object of my invention is a device whereby improved steaming effects may be obtained upon textile fabrics, thus overcoming the inequalities otherwise incident during the further operations to which the fabric is subjected.

One of the important operations to which certain classes of textile fabrics are subjected after crabbing is that of steaming. This consists in submitting the fabric in a stretched condition to the action of steam under pressure. The usually employed method is to stretch the fabric over a hollow cylinder or reel having cylindrical openings through which the steam passes into the fabric. The greatest care must be exercised in order that all portions of the fabric be equally treated as otherwise inequalities will become evident in the further dyeing and finishing operations.

I have found that this danger may be largely overcome by having certain shaped openings, not heretofore used for this purpose, in the hollow reel, and further by introducing the steam simultaneously from both ends of the reel and impinging it equally and evenly through the said openings.

In order to accomplish this I have invented a certain form of steaming machine, several modifications of which are shown in the accompanying drawings, forming a part of this application and in which similar parts are designated by similar numerals.

Figure 1 is a cross-section through the line 1—1 of Fig. 1.

Fig. 2 is a cross-section through the line 2—2 of Fig. 1.

Fig. 3 is a top plan development of a section of the foraminous plate.

Fig. 4 is a cross-section of a modification of a foraminous plate.

Fig. 5 is a top plan development of Fig. 4. 55 In the particular form of the device of my invention, shown in the accompanying drawings, a reel, around which the cloth 13 to be treated is wound, comprises the two annular end flanges 10, 10^A, to which are fixedly attached the annular foraminous plates 11, 12. The two end flanges 10, 10^A extend outwardly into the shells 14, 14^A of the hollow core of the reel. Fixedly attached to the shell 14^A is a cogged wheel 15, meshing 65 with the worm gear 16, which is fixedly attached to the shaft 17, which in turn is fixedly attached to the two gear wheels 18, 19. The gear wheel 20 is attached to the shaft 21, connected to a source of power from 70 which revolution is given to the gear wheel 20. By shifting the wheel 20, by any suitable means, the wheel 15 and the reel may be revolved in either direction or be retained at rest. 75

Extending respectively into the shells 14 and 14^A are the steam pipes 22, 22^A, around which the shells 14, 14^A revolve, a tight joint being maintained by means of the bushings 23, 23^A. 80

The foraminous plate 11 has a series of parallel elongated slits or openings 24, 24 extending longitudinally of the plate, and the inner face of the plate 11 is connected by a series of tubes 25, 25^A, 26, 26^A to the 85 exterior portion of the chambers formed by the shells 14, 14^A, the tubes from the chamber of the shell 14 alternating upon the foraminous plate 11 with the tubes from the chamber of the shell 14^A, i. e., adjacent tubes 90 opening upon the plate 11 extend oppositely to each other and outwardly through the shells 14, 14^A.

The foraminous plate 12 has a series of 95 upwardly and downwardly extended divergent openings 28, 28, between the upwardly and downwardly extended pyramidal members 29, 29. A cloth cover 30 is wound tightly around the cloth 13.

While water of condensation will have a 100 tendency to pass through the series of tubes 25, 25^A, 26, 26^A and thus outwardly of the device, in order to facilitate the removal of such water, each of the tubes 25, 25^A, 26, 26^A carries a pipe 50 having a valve 51. 105

In the modification shown in Figs. 4 and 5, the foraminous plate 12 consists of a series of parallel upwardly and downwardly ex-

tended pointed members 31, 31, between which are the openings 32, 32 through which the steam may be passed.

- The operation of the device is as follows:
- 5 The cloth 13 is wound tightly upon the foraminous plate 12 of the reel and the cloth cover 30 wound tightly around the cloth 13. The reel is then revolved and steam allowed to enter under proper pressure through the
  - 10 pipes 22, 22^A. The steam thus passes through the tubes 25, 25^A, 26, 26^A through the slits 24, 24 of the plate 11 into the chamber 33, and from thence through the openings 28, 28 of the plate 12 and through the cloth 13.
  - 15 The upwardly extending pyramidal members 29, 29 of the foraminous plate 12 support the cloth 13 in a condition where it is advantageously subjected to the action of the steam, and the tubes supplying the steam
  - 20 are so arranged that it is submitted in uniform condition to the fabric.

I do not limit myself to the particular size, form, number or arrangement of parts illustrated and described, all of which may 25 be varied without going beyond the scope of my invention as described and claimed.

What is claimed, is:

- 1. In a fabric steaming device, in combination, an outer foraminous cylinder having a series of outwardly extended members for the support of a fabric wound thereon, openings between said supporting members, a second foraminous cylinder spaced within the first cylinder and revolute therewith,
- 30 means for forcing steam through the openings of the inner cylinder, the openings of the outer cylinder and a fabric wound thereon during the revolution of the cylinders and means for revolving the cylinders.
- 35 2. In a fabric steaming device, in combination, an outer foraminous cylinder having a series of outwardly extended members for the support of a fabric wound thereon, openings between said supporting members,
- 40 a second foraminous cylinder spaced within the first cylinder and revolute therewith, tubes connecting the inner face of the inner cylinder with a source of steam supply, means for forcing steam through the openings of the inner cylinder, the openings of
- 45
- 50

the outer cylinder and a fabric wound thereon during the revolution of the cylinders and means for revolving the cylinders.

3. In a fabric steaming device, in combination, an outer foraminous cylinder having a series of outwardly extended members for the support of a fabric wound thereon, openings between said supporting members, a second foraminous cylinder spaced within the first cylinder and revolute therewith, a series of tubes extending outwardly at opposite ends of the inner cylinder and connecting the inner face of the inner cylinder with a source of steam supply, means for forcing steam through the openings of the inner cylinder, the openings of the outer cylinder and a fabric wound thereon during the revolution of the cylinders and means for revolving the cylinders.

4. In a device of the character specified, in combination, an outer foraminous cylinder having outwardly extended members having openings between them, an inner foraminous cylinder spaced from the outer cylinder and having parallel separated bars, means for revolving the cylinders in unison, tubes connecting the entire inner face of the inner cylinder with sources of steam supply, adjacent tubes upon the face of the cylinder extending in opposite directions through the device to said sources of steam supply, means for forcing steam through the device while it is revolving, and means for revolving the device.

5. In a device of the character specified, in combination, an outer foraminous cylinder having outwardly extended pyramidal members with openings between them, an inner foraminous cylinder and having parallel separated bars, means for revolving the cylinders in unison, tubes connecting the entire inner face of the inner cylinder with sources of steam supply, adjacent tubes upon the face of the cylinder extending in opposite directions through the device to said sources of steam supply, means for forcing steam through the device while it is revolving, and means for revolving the device.

HOWARD M. DUDLEY.
